UNITED STATES PATENT OFFICE.

JACOB HILDER, OF NEW YORK, N. Y.

DESIGN FOR A BELT-BODY.

SPECIFICATION forming part of Design No. 33,209, dated September 18, 1900.

Application filed July 26, 1900. Serial No. 24,947. Term of patent 7 years.

To all whom it may concern:

Be it known that I, JACOB HILDER, a citizen of the United States, residing in New York city, borough of Manhattan, State of New York, have invented and produced a new and original Design for a Belt-Body, of which the following is a specification, reference being had to the accompanying drawing, forming part hereof, which is a face view of a belt-body embodying my design.

The leading or material feature of my design consists in the shape or configuration of the end portions of the belt-body, which are curved downwardly from the back or central portion, the lower edges of the end portions being extended below the central portion of the body.

As shown in the drawing, the side portions *a* of the belt-body *A*, that extend in opposite directions from the central or back portion *a'*, are substantially symmetrical, and the end portions *b* thereof extend downwardly and outwardly on curved lines from about the points *c*, said ends projecting below the central or back portion *a'*. 25

I claim—

The design for a belt-body, substantially as shown and described.

JACOB HILDER.
